UNITED STATES PATENT OFFICE.

HOSEA H. STRAIT, OF OVERLAND, MISSOURI.

REGISTER-HOOK.

1,330,454.

Specification of Letters Patent. Patented Feb. 10, 1920.

Application filed February 18, 1919. Serial No. 277,878.

To all whom it may concern:

Be it known that I, HOSEA H. STRAIT, a citizen of the United States of America, a resident of Overland, in the county of St. Louis, State of Missouri, have invented certain new and useful Improvements in Register-Hooks, of which the following is a full, clear, and exact description, reference being had to the accompanying drawings, forming 10 a part of this specification.

My invention relates to a register hook for use in printers' chases in clamping electrotypes or other printing blocks or plates, and it has for its object the production of a 15 register hook having advantages not found in the register hooks ordinarily in use and which, due to its simplicity, is less expensive than the usual register hooks. A further object of the invention is to provide 20 a register hook of very compact form and so constructed as to afford a maximum of strength and a minimum liability of injury due to the strain imposed upon the parts in effecting a clamping operation between 25 the register hook and the part to be held thereby.

Figure I is a side elevation of one of my register hooks shown in engagement with the printing plate.

Fig. II is a vertical longitudinal section through the block shown in engagement with the printing plate.

Fig. III is a front elevation.

Fig. IV is a rear elevation.

Fig. V is a perspective view of the block and adjustable members of my register hook shown separated from each other.

In the drawings, A designates the block or main body portion of my register hook. This 40 block is provided with a semi-circular recess 1 extending from end to end of the block and open at the top of the block, so that the adjustable elements to be hereinafter described may travel throughout the length of 45 the block without any interference. The wall of the recess 1 is provided with a screw thread 2 extending throughout the length of the recess. The margins of the open top 50 of the block are preferably inclined as shown at 3.

B designates an adjustment screw operable from end to end of the recess in the block A in engagement with the screw thread 2. The screw B is of sufficient 55 diameter to project above the top of the block A, as seen in Figs. I and II, and by

so projecting affords an abutment for a particular function to be hereinafter referred to. The screw may be rotated in the block in any suitable manner, and to provide for 60 its rotation I preferably form transverse holes 4 therein for the reception of a tool, such as shown in dotted lines, Fig. IV. The screw may also contain a central non-circular hole 5 extending longitudinally of 65 the screw and to which the tool may be applied for quick action in backing up the screw.

The adjustment screw B is provided at its forward end with a circular bearing stem 6 70 of smaller diameter than the screw, this stem partaking of whatever movement is partaken of by the screw.

C designates the body of a clamping member loosely mounted on the bearing stem of 75 the adjustment screw B, so that said stem may turn within said body while the adjustment screw is moved longitudinally of the block A, the screw rotating during its movement but the clamping member body 80 partaking of only a straight movement.

The clamping member body C extends upwardly through the open top of the recess 1 in the block A and has thereon a transversely extending clamping lug 6, which extends above the top of the block A and across 85 said block so that it is in position to engage a printing plate or other printing device X resting upon the block A. By referring to Fig. II it will be seen that the lug 6 is positioned immediately in front of the peripheral portion of the adjustment screw B, which protrudes above the block A, and that therefore such peripheral portion of 90 the screw constantly serves as an abutment or backing for the lug 6. The lug 6 extends upwardly from the rearmost portion of the clamping member body C, and on said body in front of the bottom of said lug is a ledge 7, which is flush with the two top surfaces 95 of the block A and therefore affords a seat for the printing device X, the said seat extending entirely across the top of the recess 1 and preventing the descent of narrow printing devices into said recess. The 100 clamping lug 6 is preferably formed with a curved front face 6' (see Fig. V) for engagement with the printing object X, a face of this shape being desirable in order that the lug will better engage the printing object 110 if the edge of the object presented to the lug is uneven, or does not lie in a line ex-

tending at right angles to the direction of movement of the clamping lug.

In the use of my register hooks any desired number of the hooks may be located 5 within a printer's chase and locked therein by the usual furniture, and the printing plates or other printing objects are clamped between a series of register hooks by rotating the screws B in the blocks A, so that 10 the clamping member bodies C will be advanced toward the objects to be held thereby between the clamping lugs 6.

There are many advantages in my register hook over the usual register hooks, which 15 may be enumerated as follows:

The device is simple and inexpensive to manufacture, owing to the small number of parts and the simplicity of their construction. The parts are compactly arranged 20 and so disposed relative to each other as to afford a high degree of strength, and the application of strain in such manner as to avoid injury or breakage of the parts. In this latter connection, it is to be observed 25 that the clamping member body C is pressed forwardly by impact of the screw thereagainst, hence the screw exerts a pressure on the clamping portion of the device, and the screw itself, being engaged with the block 30 A back of the clamping portion, is under compression and not under tension, as is the case in the old styles of register hooks. Consequently, it is possible to make use of a very short screw to perform the desired 35 function and transmit the necessary force to the clamping portion of the device. The adjustment screw B, by projecting above the block of the register hook, lies directly back of the clamping lug 6 and therefore furnishes an abutment for the clamping lug, which avoids all possibility of the clamping lug being injured by strain, even though 40 it has only a limited connection with the clamping member body that carries it.

45 One very important combination of features of my present improvement is that of

the block having a screw threaded recess extending lengthwise therof from end to end and open at the top of the block, and the adjustment screw operable throughout 50 the length of the block without interference by any barrier, such as a bridgepiece extending across the recess. This combination renders it possible to make use of the entire length of the block A in adjusting 55 the clamping lug 6, hence smaller register hooks may be utilized and a greater number of printing objects may be held within the chase, and such objects may be arranged to better advantage than is possible in using 60 the register hooks heretofore in use.

I claim:

1. A register hook comprising a block channeled from end to end and having a screw thread extending throughout the 65 length of the block, the top of the channel being wholly unobstructed, an adjustment screw operable in engagement with said screw thread to the extreme ends of the block, and a clamping device carried by said 70 adjustment screw.

2. A register hook comprising a block having a channel therein extending from end to end of the block and having a screw thread extending throughout the length of 75 the block, the top of the channel being wholly unobstructed, an adjustment screw operable in engagement with said screw thread, said adjustment screw being of sufficient diameter to extend above the top surface of said block, and a clamping device carried by said adjustment screw, the work engaging portion of said clamping device being located above the top of the block and resting against the portion of the adjustment screw projecting above said block, whereby the strain imposed upon said work engaging portion is imposed directly against 80 said adjustment screw.

In testimony that I claim the foregoing I 90 hereunto affix my signature.

HOSEA H. STRAIT.
